UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

UNCOUPLING DEVICE FOR CAR COUPLERS.

Application filed July 21, 1924. Serial No. 727,207.

This particular invention relates to what is generally known in the art as a rotating type of uncoupling device for car couplers and comprises an operating rod revolvably mounted on the car with brackets or in any other convenient manner, which rod is usually bent downwardly at the outer end to form a handle, and is bent outwardly at its inner end to form a crank, projecting over the coupler, which crank is provided with a horizontally positioned eye over the coupler lock lifter. The standard vertical plane coupler has a knuckle pivoted to the coupler head and provided with a tail behind which the lock is placed. The lock lifter protrudes through and above the coupler head and is provided with a horizontally positioned eye. This lock lifter eye is $1\frac{1}{16}$ " in diameter and its axis is perpendicular to the longitudinal center of the car. This size and position has been determined by the American Railroad Association and is standard for the majority of couplers now in service.

My invention resides in the connection between the eye on the crank of the operating rod and the eye on the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between the coupler and the operating rod must permit such movements without the component parts becoming disengaged from each other or from either the coupler or the operating rod. It is frequently necessary to uncouple cars when they are coupled together and in contact so that it is impossible to throw the knuckle of either coupler. To meet this condition couplers are designed to assume a "lock set position" wherein the lock lifter can be raised from behind the tail of the knuckle and retained in such a position by means within the head of the coupler independent of the operating rod. This allows the operating rod to fall close to the lock lifter. (See Fig. 3.) A torsional strain is exerted on the horizontal portion of operating rod 9 by the movement of handle 12 being resisted by the coupler parts failing to operate, thus preventing the

crank arm 13 from moving upwardly. This torsional distortion alters the relation between the handle 9 and the crank arm 13 and permits the crank arm and the connector to assume the relative positions shown in Fig. 4. This is an actual service condition which must be considered. To accommodate such a movement the connection between the operating rod crank and the coupler must fore-shorten, which is accomplished by making it of several parts which collapse by means of a hinge joint or telescope each other, or as in my design, the component parts are pivotally and telescopically connected. The operating rod, as above described, is old and in use on hundreds of thousands of cars now in existence. Such rods had a short chain connecting the crank arm to the lock lifter of the coupler which chains proved unsatisfactory and were responsible for a little more than half of the defects for uncoupling mechanisms reported by the Interstate Commerce Commission. These chains were defective because they were broken, missing, kinked and either too long or too short.

One of the objects of this invention is to provide a connection between the rod and the coupler which will eliminate the defects of the old chain and meet all service conditions required.

These short chains were broken by falling behind the coupler horn and being smashed between the coupler horn and the striking casting by impact of the cars in coupling. The device is designed so that the component parts cannot become disconnected from each other or from the operating lever or the coupler. The connection between the component parts and also their connections to the operating rod and the coupler are such that the device cannot become "kinked". Formerly when a brakeman wanted a small chain to repair one of the old connections he simply guessed as to the amount of chain required and applied it to the car, which accounts for the number of "too long" and "too short" chains reported by the Commission. This is not possible with my device.

Another object is to provide a connection which may be hooked into the eye of the coupler lock lifter with the hooked member connected to the crank of the operating rod by another member which permits it to adapt itself to the various service movements of the

coupler but prevents it from becoming disengaged from the lock lifter in service.

Another object of the invention is to provide a device wherein some of the component parts are duplicates, therefore, interchangeable. Duplication, of course, also simplifies manufacture, handling, accounting, etc.

Another object of the invention is to provide a device which can be assembled at the point of manufacture and shipped as a unit to the point of application to a car and which can be applied to the car by a very simple operation which requires no special tools or appliances.

Another object is to obtain a device wherein the component parts are duplicates so that they cannot be wrongfully applied to the car or to each other.

20 In the drawings:

Fig. 1 is a perspective view of a portion of a car with my invention applied thereon.

Fig. 2 is a cross section along line 2—2 of Fig. 1 showing the device in full lines in normal position and in dotted lines in an elevated position.

Fig. 3 is a section along line 2—2 of Fig. 1 showing the device with the coupler in "lock set" position.

30 Fig. 4 is a section along line 2—2 of Fig. 1 showing the device wherein the operating rod crank arm is allowed to fall close to the lock lifter.

Figs. 5 and 6 are an enlarged side and front elevation respectively of the device assembled with the operating rod crank and coupler.

Figs. 7 and 8 are a detail side and front elevation of the hook member.

40 Figs. 9 and 10 show one of the bars in detail.

Figs. 11 and 12 show one of the pivots in detail.

Fig. 13 is an enlarged side elevation of a modified design in assembled relation.

Fig. 14 is an enlarged front elevation of a modified design in assembled relation.

Figs. 15 and 16 show the bars of the modified design in detail.

50 The usual parts of the car are shown wherein 1 is the end sill; 2 the push pole pocket; 3 the striking casting; 4 the carry iron; 5 the coupler; 6 the coupler knuckle; 7 the knuckle pivot; 8 the lock lifter and 15 the lock lifter eye.

A rod 9 is revolvably mounted in brackets 10 and 11 which are secured to any convenient part of the car. The rod 9 is bent downwardly at the outer end to form handle 12 and bent laterally at the inner end to form the crank 13 which is provided with a horizontally disposed eye 14. This form of operating rod was formerly a universal standard and is therefore on hundreds of thousands of cars now in service. The eye

15 of the lock lifter 8 and the eye 14 of the crank 13 have their axes parallel to each other and perpendicular to the longitudinal axis of the car.

The preferred form of my device comprises a connection between the crank 13 and the coupler lock lifter 8 comprising a member 16 having an open hook 17 which is inserted through the eye 15 of the lock lifter. The upper end of this hook member 75 is provided with a closed eye 18 (which may be elongated vertically if desired) which is pivoted to a pair of bars 19—20, which bars are pivoted at their upper ends to the crank arm at 21 by means extending 80 through the crank arm eye.

The pivotal joint 22 between the pair of bars 19—20 and the hook member 16 provides a hinge action so that the component parts of the connector may collapse to allow 85 the crank to return to normal position when the coupler is in lock set position. (This is shown in Fig. 3.) The bars are spaced far enough apart to permit the hook to adapt itself to the lateral movement of the coupler without binding or bending the parts. The lower ends of the bars are extended downwardly at 23—24 to limit or restrict the lateral swing of the hook member 16 relative to the bars 19—20 so that the hook cannot swing far enough to either side 90 to be disengaged from the lock lifter eye when the device is assembled on a car. The pivot member 25 is substantially the same diameter as the horizontal width of the eye 18 so that the hook member cannot rotate 100 sufficiently on its longitudinal axis to permit disengagement from the lock lifter eye. The eye 18 may be elongated vertically to provide a telescopic movement between the 105 component parts.

Another object of this telescopic arrangement and the hinge arrangement is so that the device may be applied to different cars wherein there are varying vertical distances 110 between the crank eye and the lock lifter eye.

The pivotal joint 21 between the bars 19—20 and the crank arm 13 allows for the fore and aft movement of the coupler in 115 service. The hook connection between the device and the lock lifter eye also permits the fore and aft movement of the coupler.

The device is assembled at the point of manufacture by peening or riveting over 120 both ends 26—27 of pivot 25 after the hook member 16 and the two bars have been assembled. One end of the pivot (27) is not tightened so that the bar 20 can assume an oblique position, as shown by dotted lines 125 in Fig. 6, or can rotate around pivot 25. The upper pivot 28 is placed in the upper hole 29 of one of the connecting rods and peened or riveted over (30) but the other end (31) of this pivot remains normal. 130

The device is sent to point of installation in this condition. In applying the device to the car the hook is inserted through the eye of the lock lifter and then the upper pivot 5 28 is inserted through the eye 14 of the crank arm and then the end 31 of the pivot 28 is inserted through the upper hole 32 of the loose connecting rod 20 and the installation is completed by merely peening or 10 riveting over the end 31 of the pivot.

It will be noted that the line of thrust between the operating rod and the coupler is symmetrical about a straight line so that there is no eccentric load to distort or twist 15 the device.

The connecting rods 19—20 are duplicates and also the pivot members 25—28 are duplicates. This is not only for simplicity in manufacture but also facilitates assembling 20 and installation, and, furthermore reduces the possibilities of the device being improperly assembled or installed.

Figs. 13, 14, 15 and 16 show a modification wherein one of the pivots 50 is integral 25 with one of the connecting rods 51, and, furthermore, the two connecting rods 51—52 (with their integral pivots) are duplicates. In assembling the device the ends 53 and 54 are bent over, as shown in Fig. 14.

30 I claim:—

1. A connector for a railway car coupler operating rod crank arm having a horizontally disposed eye and a coupler lock lifter having a horizontally disposed eye, said connector comprising a pair of bars arranged to be disposed on the opposite sides of the crank arm and pivoted thereto through the crank eye, and a hook arranged to be operatively connected to the lock lifter eye at its 35 lower end and having an eye at its upper end pivotally, substantially non-rotatively and laterally swingingly connected to said bars.

2. A connector for a railway car coupler operating rod crank arm having a horizontally disposed eye and a coupler lock lifter having a horizontally disposed eye, said connector comprising a pair of bars arranged to be disposed on the opposite sides of the crank arm and pivoted thereto through the 40 crank eye, and a hook arranged to be operatively connected to the lock lifter eye at its lower end and having an elongated eye at its upper end pivotally, substantially non-rotatively and restrictively laterally swingingly connected to said bars.

3. A connector for a railway car coupler operating rod crank arm having a horizontally disposed eye and a coupler lock lifter having a horizontally disposed eye, said connector comprising a pair of bars arranged to be disposed on the opposite sides of the 45 crank arm and pivoted thereto through the 50

crank eye, and a hook arranged to be operatively connected to the lock lifter eye at its lower end and having its upper end pivotally, substantially non-rotatively and restrictively laterally swingingly connected to said bars. 65

4. A connector for a railway car coupler operating rod crank arm having a horizontally disposed eye and a coupler lock lifter having a horizontally disposed eye, said connector comprising a pair of bars arranged to be disposed on the opposite sides of the crank arm and pivoted thereto through the 70 crank eye, and a hook arranged to be operatively connected to the lock lifter eye at its lower end and having an eye at its upper end substantially non-rotatively connected to said bars. 75

5. A connector for a railway car coupler operating rod crank arm having a horizontally disposed eye and a coupler lock lifter having a horizontally disposed eye, said connector comprising a pair of bars arranged to be disposed on the opposite sides of the crank arm and pivoted thereto through the crank eye, and an open hook arranged to be operatively connected to the lock lifter eye at its lower end and having a single elongated eye at its upper end substantially non-rotatively connected between said bars. 80

6. A connector for a railway car coupler operating rod crank arm having a horizontally disposed eye and a coupler lock lifter having a horizontally disposed eye, said connector comprising a pair of bars arranged to be disposed on the opposite sides of the crank arm and pivoted thereto through the crank eye, and an open hook arranged to be operatively connected to the lock lifter eye at its lower end and having its upper end substantially non-rotatively connected between said bars. 85

7. A connector for a railway car coupler operating rod crank arm having a horizontally disposed eye, and a coupler lock lifter having a horizontally disposed eye, said connector comprising a hook operatively engaging the lock lifter eye at its lower end, and provided with an eye at its upper end, a pivot extending through the eye of the said hook, another pivot extending through the eye of the operating rod crank, and a pair of duplicate bars connecting the opposite ends of said pivots. 90

8. A connector for a railway car coupler and its operating rod, said connector comprising a pair of spaced apart bars and a hook member, said hook member pivotally, substantially non-rotatively and restrictively laterally swingingly connected to and between said bars. 100

GARTH G. GILPIN.
